Primary Examiner — Elizabeth Albert(74) *Attorney, Agent, or Firm* — Craig & Craig, LLC; R. Sean Hocking(57) **CLAIM**

I claim the ornamental design for a construction helmet desk caddy, as shown and described.

DESCRIPTION

FIG. 1 is a perspective view of the construction helmet desk caddy showing my new design;

FIG. 2 is a right side view of the design shown in FIG. 1, where the left side view is a mirror image to the right side view shown in FIG. 2;

FIG. 3 is a front view of the design shown in FIG. 1;

FIG. 4 is a rear view of the design shown in FIG. 1;

FIG. 5 is a top view of the design shown in FIG. 1; and,

FIG. 6 is a bottom view of the design shown in FIG. 1. The broken lines shown in FIG. 5 and FIG. 6 of the construction helmet desk caddy are shown for the purpose of illustrating portions that form no part of the claimed design.

The nature of the invention is an ornamental design for a construction helmet desk caddy of the sort intended for use in the storage of pens, business cards and other like utensils.
